UNITED STATES PATENT OFFICE.

BRUCE J. DAVIDSON, OF MARSEILLES, ILLINOIS, ASSIGNOR TO WIREBOUNDS PATENTS COMPANY, A CORPORATION OF MAINE.

MACHINE FOR USE IN MAKING BOXES.

Application filed October 28, 1920. Serial No. 420,210.

To all whom it may concern:

Be it known that I, BRUCE J. DAVIDSON, a citizen of the United States, and a resident of Marseilles, in the county of La Salle and State of Illinois, have invented an Improvement in Machines for Use in Making Boxes, of which the following is a specification.

The invention relates to machines for use in fastening heads, ends, partitions or the like to boxes, crates and the like.

Among other objects the invention is intended to provide a machine of the class described, having improved means for controlling or positioning the work during a fastener driving operation.

The invention will be best understood by reference to one illustrative embodiment thereof shown in the accompanying drawings in which:

Fig. 1 is a general perspective view of a machine embodying the invention.

Fig. 2 is a side elevation of the machine showing a crate partly broken away in position to be operated upon.

Fig. 3 is an enlarged top plan view of the nose of the machine showing the work controlling means.

Fig. 4 is an enlarged front elevation of the nose of the machine showing a crate in position to be operated upon.

Figs. 5, 6 and 7 are plan views of the nose of the machine showing a crate being operated upon in different positions; in these figures for clearness of illustration, the lower arm which carries the staple driving mechanism is shown in full lines and the upper arm which carries the work controlling means is shown in dotted lines.

Fig. 8 is an enlarged perspective of the work controlling means for positioning the work.

Fig. 9 is a top plan view of the same.

Fig. 10 is a front elevation of the same.

Fig. 11 is a sectional view taken on the line A—A of Fig. 9.

Fig. 12 is a perspective of one end of a wirebound crate showing an end stapled to the cleats of the crate sides.

One illustrative type of crate upon which the machine is designed to operate is partly illustrated in Fig. 12. This illustrative

crate is a wirebound crate comprising four side sections of slatted side material *a* and cleats *b* connected together in foldable relationship with binding wires *c* stapled thereto, and heads or ends *d* stapled to the cleats *b* of one or more side sections by staples *e*. In practice the materials for the four sides of the crate are usually assembled and secured together in a crate blank machine which connects the four sides of the crate with wires producing what is commonly referred to as a crate blank. The blank is then partially folded about the heads or ends *d*, as shown in Fig. 12 and the heads or ends are then fastened to the side cleats *b*.

The illustrative machine is for use in performing this head or end fastening operation and is designed to operate within the crate, close to the sides thereof and in the corners and to drive staples through the head or end *d* and into or through the cleats *b*.

As illustrated in Fig. 1 the invention is embodied in an end stapling machine of the type disclosed in the patent to Thompson, #1,295,237, issued February 25, 1919, consisting generally of staple forming and driving mechanism, and clamping or clinching mechanism to cooperate therewith during a staple driving operation. It will be understood, however, that the invention is not limited to the particular end stapling machine illustrated but may be embodied in other types of which there are several.

The illustrative machine is supported by the frame 1 which carries arms 2 and 3 having an opening therebetween to permit the insertion of a box or crate and its end or head as shown in Fig. 2. Arm 2 which carries the staple driving mechanism is formed with a narrow nose adapted to enter a box or crate, close to the sides thereof and in the corners and arm 3 carries the clincher mechanism for clamping the box or crate parts in position during the staple driving operation and for clinching any staples that may be driven through the materials. Staples 4 are formed from wire 5 by staple forming mechanism (not shown) located at the rear of the machine and are fed forward to the nose of arm 2 with their

points upstanding in the manner illustrated in said patent to Thompson above referred to. From the nose of arm 2 the staples are driven upward through the head or end *d* into the cleats *b* of the crate or box.

The mechanism for forming, feeding and driving the staples and the clincher mechanism need not be shown or described in detail as said mechanisms are fully shown 10 and described in the patent to Thompson above referred to.

In operation a head or end *d* is placed upon the upper surface of the lower arm 2 and the three sides of the box or crate are 15 wrapped about the head or end *d* with the cleats *b* above the end *d*. Staples are then driven at intervals through the head or end *d* and into the cleats *b* of side sections of the box or crate. For clearness of description 20 the side sections of the crate illustrated in Figs. 5, 6 and 7 have been designated *S*, *S'* and *S²*. Staples are usually driven into the cleats of all three of these sections although in some instances it has not 25 been found necessary to drive staples into more than two of said sections.

To increase the holding power of the staples it is desirable to drive them along the longitudinal center line of the cleats. 30 As shown in Fig. 5, therefore, the driving point *X* is located at such a distance relative to the nose of the arm 2 that when a box or crate is placed upon said arm the side material of the crate or box will not prevent 35 the proper positioning of the cleat over the driving point.

Heretofore, as in the machine of the Thompson patent above referred to, the work was positioned for a stapling operation 40 by the nose of the stapling arm which contacted with or engaged the side material of the box as it was pressed against the nose by the operator and as the box was shifted for each stapling operation the nose 45 of the stapling arm dragged along the inner surface of the side material at all times positioning the driver relative thereto and relative to the cleat. Such a work-controlling means is effectual for positioning a 50 box having in effect, integral or continuous side material. It has been found in practice, however, that when a crate having openings in the side material is being operated upon that the nose of the stapling arm 55 often catches in such openings or partially passes through them thus improperly positioning the work, causing inaccurate positioning of staples and otherwise delaying the stapling operation.

60 In the illustrative machine, work controlling means for properly positioning the materials for the fastening operation, regardless of openings in the sides of the work, is provided.

65 As illustrated, said means takes the form

of an independent attachment to the under side of the nose of upper arm 3, but it will be understood that the work-controlling means may be formed as an integral part of the machine without departing from the invention. 70

The illustrative work-controlling means is designed to position or gauge the work for a stapling operation from the cleat *b* of the illustrative crate, which as shown in 75 Fig. 12, has no openings into which the work-controlling means may enter as the work is shifted for successive operations.

Referring to Figs. 8 to 11 the illustrative work-controlling means comprises a member 6, adapted to engage the cleats of a box or crate and so position the parts relative to the staple driving mechanism that the cleat will be properly positioned over the staple driving mechanism and the side material of the box or crate will be held clear of any engagement with the nose of the lower arm 2. 80

To facilitate shifting the work for successive stapling operations said member 6 is preferably rotatable and in the present instance takes the form of a roller against which the cleat of the box or crate is pressed. 90

In practice, side *S* is usually stapled by shifting the side across the stapling plane at approximately right angles to the longitudinal center line of the stapling arm 2 so that the work will be properly positioned for a stapling operation regardless of the position of the member 6 relative to the longitudinal center line of the stapling arm. 95

Sides *S'* and *S²* however, as shown in Figs. 6 and 7 are pressed toward the side of the stapling arm and shifted on an angle corresponding to the angle of the side of the arm relative to its longitudinal center line. To properly position the parts when the sides *S'* and *S²* are being stapled provision is made for shifting the position of the member 6 relative to the longitudinal center line of the stapling arm so that the cleats of the sides *S'* and *S²* may be properly positioned for a stapling operation. 110

As shown in Figs. 8, 9, 10 and 11, member 6 is carried by a bar 7 reciprocable 115 horizontally in guides 8 in the body member or frame 9 which in the present instance is adjustably secured to the under side of the upper arm 3 by set screws 10 or in any other suitable manner. 120

To limit the reciprocations of bar 7, to control the position of the member 6, said bar is provided with a member 11 adapted to contact alternately with members 12 and 13 respectively carried by the body member 9. Members 12 and 13 which in the present instance take the form of screws may be adjusted to control the extent of reciprocation of the bar 7 thus controlling the position of the member 6. 130

As shown in Fig. 6, the cleat of section S' has pressed member 11 to the limit of its reciprocation against member 13 which has been adjusted to properly position member 6 to control the position of the work while section S' is being operated upon and, as shown in Fig. 7, the cleat of section S² has pressed the member 11 to its other limit of reciprocation against member 12 which has similarly been adjusted to properly position member 6 to control the position of the work while section S² is being operated upon.

Thus it will be noted that work-controlling means is provided to properly position the work and prevent the nose of the stapling arm from entering openings or spaces in the side material; that said means is rotatable and reciprocates in response to the shifting of the work thus automatically adjusting itself to the movement and position of the work; and that said means gauges or positions the work from the cleats.

Obviously the invention is not limited to the specific embodiment illustrated and described, which may be variously modified in details of construction and arrangement, and features of the invention may be used in various machines embodying the invention, and in various combinations and sub-combinations.

Having described the invention what is claimed is:

1. In a box or crate end stapling machine which is constructed and arranged to operate within a box or crate to fasten a head or end to cleats thereof, the combination of fastener-driving mechanism and cleat-engaging means to position the work relative to said mechanism.

2. In a box or crate end stapling machine which is constructed and arranged to operate within a box or crate to fasten a head or end to cleats thereof, the combination of fastener-driving mechanism and means to relatively position said mechanism and the work including a member adapted to engage a cleat of the box or crate.

3. In a box or crate end stapling machine which is constructed and arranged to operate within a box or crate to fasten a head or end thereto, the combination of fastener-driving mechanism and movable means to relatively position said mechanism and the work.

4. In a box or crate end stapling machine having fastener-setting mechanism constructed and arranged to operate within a box or crate to fasten a head or end thereto, movable work-controlling means to position the work for a fastening operation.

5. In a box or crate end stapling machine having fastener-setting mechanism constructed and arranged to operate with-

in a box or crate to fasten a head or end thereto, movable work-controlling means to position the work for a fastening operation automatically adjustable by pressure of the work thereagainst.

6. In a box or crate end stapling machine having fastener-setting mechanism constructed and arranged to operate within a box or crate to fasten a head or end thereto, rotatable work-controlling means to position the work for a fastening operation.

7. In a box or crate end stapling machine having fastener-setting mechanism constructed and arranged to operate within a box or crate to fasten a head or end thereto, work-controlling means shiftable with the work to properly position the work for successive fastener-setting operations.

8. In a box or crate end stapling machine which is constructed and arranged to operate within a box or crate to fasten a head or end thereto, the combination of fastener-driving mechanism and means to relatively position said mechanism and the work including a rotatable member adapted to engage the work.

9. In a box or crate end stapling machine which is constructed and arranged to operate within a box or crate to fasten a head or end thereto, the combination of fastener-driving mechanism and means to relatively position said mechanism and the work including a movable member adapted to engage the work.

10. In a box or crate end stapling machine having a stapling arm adapted to operate within a box close to the sides thereof and in the corners to fasten a head or end to cleats of a cleat reinforced box or crate, means to prevent the nose of said arm from entering openings in the sides of the box or crate.

11. In a box or crate end stapling machine having a stapling arm adapted to operate within a box close to the sides thereof and in the corners to fasten a head or end to cleats of a cleat reinforced box or crate, means to position the work for a stapling operation and to prevent the nose of said arm from entering openings in the sides of the box or crate.

12. In a box or crate end stapling machine having a stapling arm adapted to operate within a box close to the sides thereof and in the corners to fasten a head or end to cleats of a cleat reinforced box or crate, means to prevent the nose of said arm from entering openings in the sides of the box or crate comprising a movable work-engaging member.

13. In a box or crate end stapling machine having a stapling arm adapted to operate within a box close to the sides thereof and in the corners to fasten a head

- or end to cleats of a cleat reinforced box or 45
crate, means to position the work for a
stapling operation and to prevent the nose
of said arm from entering openings in the
sides of the box or crate comprising a work-
engaging member shiftable in accordance
with the shifting of the work.
14. In a box or crate end stapling machine 50
having a stapling arm adapted to
operate within a box close to the sides thereof
and in the corners to fasten a head or
end to cleats of a cleat reinforced box or
crate, means to position the work for a 55
stapling operation and to prevent the nose
of said arm from entering openings in the
sides of the box or crate comprising a move-
able gauge and means to control the move-
ment thereof.
15. In a box or crate end stapling machine 60
having a stapling arm adapted to
operate within a box close to the sides thereof
and in the corners to fasten a head or
end to cleats of a cleat reinforced box or
crate, means to position the work for a 65
stapling operation and to prevent the nose
of said arm from entering openings in the
sides of the box or crate comprising a cleat-
engaging member movable to different pos-
itions in accordance with movements of the
work.
16. In a box or crate end stapling machine 70
having a stapling arm adapted to
operate within a box close to the sides thereof
and in the corners to fasten a head or
end to cleats of a cleat reinforced box or
crate, means to position the work for a 75
stapling operation and to prevent the nose
of said arm from entering openings in the
sides of the box or crate comprising a work-
engaging member shiftable automatically
by pressure of the work thereagainst.
17. In a box or crate end stapling machine 80
which is constructed and arranged to op-
erate within a box or crate to fasten a head
or end thereto, the combination of fastener-
driving mechanism, movable work-con-
trolling means and means to control the
movement thereof.
18. In a box or crate end stapling machine 85
having a stapling arm adapted to
operate within a box close to the sides thereof
and in the corners to fasten a head or
end to cleats of a cleat reinforced box or
crate, means to position the work for a 90
stapling operation and to prevent the nose
of said arm from entering openings in the
sides of the box or crate comprising a move-
able gauge and means to control the move-
ment thereof.
19. A machine for use in fastening heads
or ends to cleats of a cleat reinforced crate
having a narrow nose adapted to operate 95
within a crate close to the sides thereof and
in the corners which comprises staple-form-
ing mechanism; staple-driving mechanism
adapted to drive a staple from said nose;
and means to prevent said nose from en- 100
tering openings in the crate side.
20. A machine for use in fastening heads
or ends to cleats of a cleat reinforced crate
having a narrow nose adapted to operate 105
within a crate close to the sides thereof and
in the corners which comprises staple-form-
ing mechanism; staple-driving mechanism
adapted to drive a staple from said nose;
and means to position the work and 110
to prevent said nose from entering open-
ings in the crate side.
21. In a box or crate end stapling machine 115
having a stapling arm constructed and ar-
ranged to operate within a box or crate to
fasten a head or end to cleats thereof, means
to position the box or crate and to prevent
the nose of said arm from entering openings 120
in the box or crate sides comprising the
movable gauge member 6 substantially as
set forth and described.

In testimony whereof, I have signed my
name to this specification.

BRUCE J. DAVIDSON.
